UNITED STATES PATENT OFFICE

152,538

DESIGN FOR A COMBINED CAP AND LATCH
FOR SCREEN HOLDER

John T. Heck, Elmhurst, and Leo J. Du Mais and
Curtis O. Talbot, Chicago, Ill., assignors to Da-
Lite Screen Company, Inc., Chicago, Ill., a cor-
poration of Illinois

Application July 3, 1947, Serial No. 140,094

Term of patent 14 years

(Cl. D61—1)

To all whom it may concern:

Be it known that we, John T. Heck, residing at Elmhurst, in the county of Du Page and State of Illinois, Leo J. Du Mais, residing at Chicago, in the county of Cook and State of Illinois, and Curtis O. Talbot, residing at Chicago, in the county of Cook and State of Illinois, all citizens of the United States of America, have invented a new, original, and ornamental Design for Combined Cap and Latch for Screen Holder, of which the following is a specification, reference being had to the accompanying drawing, forming part thereof.

Figure 1 is a perspective view of a combined cap and latch for screen holder, showing our new design.

Figure 2 is a perspective view thereof.

Figure 3 is a side elevational view thereof.

Figure 4 is an end elevational view of Figs. 1 and 2 looking from the right hand side.

Figure 5 is a bottom elevational view thereof.

We claim:

The ornamental design for a combined cap and latch for screen holder, as shown.

JOHN T. HECK.

LEO J. DU MAIS.

CURTIS O. TALBOT.
